FLOOR STRUCTURE

Harry D. Fenske, Dearborn, Mich., assignor to
 National Steel Corporation, a corporation of
 Delaware

Application November 15, 1947, Serial No. 786,198

2 Claims. (Cl. 189—34)

1

The present invention relates to improvements in metal structural elements, relating more particularly to steel structural members especially useful for constructing floors over which freight is moved or upon which it is stored, such as floors for freight cars, trucks, warehouses and the like.

Recently, attempts have been made to replace with steel flooring elements the heavy wooden planking forming the conventional floor surface of a freight carrying conveyance or of a storage building; because wooden floors wear excessively, they are expensive to repair or replace and in many instances they do not possess the desired strength. Such attempts have been only partially successful, however; for serious difficulties have been encountered.

Obviously, steel floor elements have presented a problem in so far as nailing blocks in place is concerned or in nailing guide rails, frame members, etc. to the floor in accordance with the customary practice for preventing freight from shifting undesirably. Consequently, it has been proposed to use freight car floors of a composite construction formed of steel having wooden inserts. Such floors have not been suitably dependable to haul all kinds of freight and the wooden inserts must be replaced often, which is objectionable. In addition, such composite floors are expensive to manufacture and install.

Whether the car flooring consists of the composite construction mentioned or is of an all-steel construction, the floor tends to become dangerously slippery. This unfortunate tendency is accentuated when oil, water, fine freight, etc. are spilled on the floor, not to mention the polishing effect of the wheels of hand trucks, loading devices and the like. As a result, steel floors attain a very low coefficient of friction so that the angle of repose of an article or load carried by the floor is necessarily small. Consequently, resistance to shifting or sliding is slight causing the load to move about undesirably on the slightest provocation. Such shifting is particularly undesirable for floating loads; that is, loads which are permitted to move in a limited manner relative to the conveyance. Accordingly, on former steel floors it has been most difficult to block or otherwise to control floating loads and it has proved almost as difficult to block or satisfactorily secure other loads in place since they tend to shift or move so easily.

Another serious difficulty encountered in connection with channel-shaped steel floor members is so-called "dishing," that is excessive denting or longitudinal deformation of the load-bearing panel of the channel members which is prin-

2

pally due to the dropping of heavy articles upon the floor or to the action of heavily loaded lift trucks which are driven upon it. Such dishing is, of course, undesirable for among other things it makes the floor uneven so that loading and unloading becomes difficult. It makes proper removal of fine ladings very difficult and it damages the floor members as well as causing undue wear and corrosion thereof.

10 It is, therefore, one of the principal objects of the present invention to provide a metal structural element especially useful as a floor member, which element is markedly stronger than comparable elements without having an appreciably increased metal content. Accordingly, the present structural element can withstand hard usage without requiring repair or replacement but is economical to manufacture.

Another object of the invention is to provide 20 an improved structural element having a smooth planar load-bearing face resistant to deformation and wear while presenting a non-skid surface which does not become slippery with use or because of spilled freight and which lasts throughout the useful life of the member itself.

25 It is another and somewhat more specific object of the invention to provide an improved generally channel-shaped steel floor member having a load-bearing panel containing strengthening indentations or depressions filled with a wear resistant non-metallic substance so that the floor member not only is strengthened but at the same time presents a smooth durable non-skid surface and is therefore considerably safer, particularly in connection with the storing and moving of freight which necessarily subjects a floor to heavy loads, hard usage and to the damaging action of oil, water, sand and many other corrosive or abrasive materials.

30 Still another object of the invention is to provide a floor composed of a plurality of floor members of the aforementioned general character and to provide such members with a structure permitting them to be placed side by side conveniently and effectively but spaced from each other to provide grooves or openings for receiving nails. Since each floor member possesses a strengthened structure it is adapted to withstand its load without support from adjacent members so that the floor not only remains smooth but dishing is almost entirely avoided. As a consequence, the nail receiving grooves do not spread and are not otherwise deformed so that their effective operation is not impaired or prevented by dishing of the floor members as has often 35 been the case heretofore.

Finally, it is an object of the invention to provide an improved metallic nailable interior surface for freight conveyances or the like in which nailing grooves, as well as indentations or depressions in the load-bearing surface, are filled with a mastic or cementitious material rendering the freight conveyance suitable for carrying all kinds of ladings including loose or unpackaged cargoes such as grain, sand, etc. without loss through cracks, grooves, nailholes, split structural elements and the like; and to provide a surface possessing and retaining a relatively high coefficient of friction as compared with slippery all-metal surfaces or composite metal and wooden surfaces, so that floating loads may be conveyed effectively and safely and other loads may be securely blocked or fastened in place more conveniently and easily.

Other objects and advantages of the present invention are in part obvious and will in part appear from the following detailed description and appended claims taken in connection with the accompanying drawings in which:

Figure 1 is a horizontal, fragmentary, cross-sectional view of a freight car embodying the present invention.

Figure 2 is an isometric view of a portion of the floor structure of the freight car illustrated in Figure 1 and is taken along the line 2-2 of Figure 1 in the direction of the arrows.

In the drawings, there is illustrated a freight car of the box-type having a floor structure constructed in accordance with the present invention. This floor structure is shown as a whole at 9. Except for the structure of the floor, which is described in detail hereinafter, the structure of the boxcar illustrated is well-known and, in fact, constitutes a standard type of car in widespread use. Accordingly, there is illustrated in the drawings only that portion of the car's structure which is located adjacent to or supports the floor or is otherwise directly related thereto.

Referring to Figure 1, the boxcar partially illustrated includes a pair of longitudinally extending side angle members 10 and 11. These angle members are supported by cross-bearers or cross-beams (not shown) spaced at intervals throughout the length of the car. The cross-beams or cross-bearers are joined to and extend laterally from a central longitudinal sill member 25 and rest upon suitable sills or other structural members included in the basic framework of the car, which framework carries the wheels and other operating parts and mechanisms.

The reference numeral 12 designates metallic sheathing, preferably in the form of panels which comprise the so-called skin plates forming the outer side walls of the car. The metallic sheathing or plates are secured in place by being welded or otherwise firmly attached to the upright legs of the angle members 10 and 11. Preferably, they are also attached to the cross-bearers and to the sills or other structural members supporting the cross-bearers. At the corners of the car, the wall plates 12 are secured to an upright angle member 13 having flanges 14 and 15 right-angularly turned from the outer margin of each of its legs. One of these flanges is utilized to provide a suitable surface for attaching the sheathing 12 to the angle member. The other flange is utilized to provide a similar attaching surface for metal sheathing or plates 16 comprising the outer end wall of the car. The sheathing or plates 16 are secured in place in a manner similar to the sheathing or plates 12, previously mentioned, and

the angle members 13 are welded or otherwise firmly secured to the frame of the car so that the sheathing 12 and 16 and the angles 13 provide a rigid wall structure enclosing the interior of the car. A curved cover plate 17 having a rounded corner is attached to the sheathing 12 and 16 at the corners of the car in order to reinforce the structure and to conceal the angle members 13.

The reference numeral 18 designates an inner wooden side wall or lining which is spaced from the outer metallic wall 12 and is held in place by suitable studs or upright supporting members spaced at intervals, two such studs being shown at 20 and 21. The end wall of the car also is provided with a wooden inner wall or lining 19 placed directly against the outer metallic end wall 16. The wooden inner wall or lining 18, 19 preferably rests upon suitable supports such as the side angle members 10 and 11 and may be reinforced if desired. For example, corner pieces 22 may be utilized.

Referring in detail to the structure of the floor 9, one of the structural members forming a part of the floor is indicated generally at 27, and includes a surface panel or plate 29 provided with a pair of depending downturned webs 30 and 31, one of which extends along the margin of each side of the panel. Flanges 32 and 33 extend inwardly from the lower or projecting marginal edge of each of the webs 30 and 31, that is from the edge removed from the panel 29, so that the structural member 27 is generally channel-shaped. Intermediate the depth of each of the webs 30 and 31, there is a corrugation extending along its length. Each corrugation is spaced from the panel 29 so that a straight portion is presented by the web extending from the panel to the corrugation. The corrugation in one of the webs extends inwardly whereas the corrugation in the other web extends outwardly. Accordingly, both corrugations are concavo-convex in shape; but one provides a concave indentation in the outer surface of the web, whereas the other presents a convex ridge therein. In the particular form of the invention illustrated, the indentation is formed in the web 30 and the ridge in the web 31.

As best shown in Figure 1, the floor is composed of a plurality of the structural members 27 which extend transversely across the width of the freight car. These members are arranged side by side in a contiguous manner but adjacent members are spaced apart somewhat to provide a transverse groove or slot between each pair of the members. As best shown in Figure 2, the members 27 are so positioned that an indentation or inwardly bent corrugation in one web, such as the corrugation in the web 30, mates with a complementary ridge or outwardly bent corrugation in the adjacent member 27, such as the ridge in the web 31. It will be observed that the indentation possesses a somewhat larger radius of curvature than does the ridge. Furthermore, the construction and arrangement is such that each set of mating ridges and indentations is curvilinearly parallel causing the width of each groove or slot between adjacent members 27 to be substantially uniform throughout its depth. Preferably, this width is approximately equal to the thickness of a nail. Thus, a nail may be driven into the groove and be bent or deformed for clinching it. The groove is adapted to maintain the nail normal to the surface of the floor and the plurality of such grooves provides ready and convenient means for nailing, fastening or re-

taining elements to the floor, such for instance, as the block 35. In order that the freight conveyance containing the floor 9 may be used to haul fine freight such as grain, sand, or unpackaged materials without danger of loss, the nailings or grooves are filled with a relatively soft, mastic or gummy material 49 acting as a sealant but which is adapted to receive a nail.

One end of each of the contiguous floor members 27 rests upon one of the side rails or angle members 10 or 11. The floor members 27 are also supported by longitudinal frame members 23 as well as by the central longitudinal sill member 25. The frame members 23 are preferably Z-shaped and are supported by the cross-beams or cross-bearers (not shown) forming a part of the car frame and mentioned hereinbefore. The reference numerals 26 and 28 designate a pair of wooden strips disposed between the central sill member 25 and the floor members 27. It is preferable to fasten the floor members directly to supporting frame members, such as the members 23 and the sill 25, but it is sometimes necessary to use fillers such as the strips 26 and 28 in order to provide a level floor while utilizing the previously constructed framework of the car. The strips 26 and 28 may be formed of steel and welded to the floor members 27. Each end of each member 27 may be riveted to the angle members 10 or 11 while its intermediate portion may be welded to one or more of the Z-shaped supports 23. It will be noted that each member 27 is attached to its support independently of its adjacent member. Thus, such members are easy to repair or replace.

The increased strength of the present floor members 27 prevents dishing or deformation thereof especially at the panel portions 29. Consequently, the nail receiving grooves are not spread or otherwise distorted by such dishing and remain fully operative throughout the useful life of the floor members. If necessary, the floor members can be secured together to strengthen the floor 9 especially to make it more rigid and resistant to swaying or buckling longitudinally of the conveyance. For instance, bridge-welds may be used at spaced points along the top of each nailning groove to secure the floor members to each other. However, when the floor members 27 are not physically attached to each other, except for the mastic material or the like filling the nailning groove, the strengthened structure of each member 27 causes it to resist dishing. Accordingly, in this case, too, the nail receiving grooves do not spread and are not distorted.

The outer or load-bearing surface of the panel 29 forming a part of each floor member 27 is provided with a plurality of indentations or depressions 36 herein sometimes referred to as reinforcing ribs. In the form of the invention illustrated, these indentations and depressions are somewhat elongated, that is, they are relatively long as compared with their width. The indentations or depressions 36 are provided with a round or semi-circular contour in cross-section but possess upwardly inclined converging end walls which meet to provide a rounded end point smoothly merging into the surface of the panel 29. The indentations or depressions 36 are spaced from each other longitudinally throughout the length of each member 27, the major axis of each indentation running transversely of the member 27. In fact, these major axes are right angularly disposed relative to the longitudinal axis of the member 27. Therefore, the depre-

sions or indentations 36 are not only arranged in a contiguous manner, but they are parallel to each other.

It should be understood that the aforementioned arrangement of the indentations or depressions 36 disposes the major axes thereof at right angles relative to the parallel longitudinal axes of the webs 30 and 31. As a result, the members 27 are strengthened against longitudinal deformation of the panels 29 inasmuch as the transversely extending depressions 36 stoutly resist such deformation. Thus, the severe loading imposed by wheels of lift trucks or the like running on the panels 29 in order to cross the width of the floor 9 do not dish the floor. The webs 30 and 31 provide ample strength for resisting transverse deformation of the member 27 if lift trucks are run lengthwise of the boxcar or if such transverse loading is otherwise imposed.

While the above described particular structure and arrangement of the indentations or depressions 36 is preferable, suitable changes or variations in the shape and arrangement thereof could be made without departing from the spirit of the present invention. For example, the major axes of the depressions 36 could run obliquely relative to the longitudinal axes of the webs 30 and 31, and the depressions or indentations do not necessarily have to be parallel although it is more practical to so arrange them. Also, the shape of the depressions or indentations 36 could differ from that illustrated provided that the surface of the panel 29 is kept smooth. Principally because of the elongated shape of the member 27, it is much better to provide a somewhat elongated indentation or depression 36 so that it may extend across substantially all of the width of the panel 29 in order to strengthen the panel more effectively.

The depressions or indentations 36 are filled with an initially moldable non-metallic, mastic surfacing material adapted to set or harden into a durable rock-like product. These depressions or indentations are filled flush with the surface of the panel 29 to provide a smooth, planar surface for each floor member 27 and for the floor 9. One suitable material comprises an asphaltic bonding agent, an inert aggregate, an asphaltic base, and a cementitious setting agent. More particularly, I have successfully employed as the bonding agent a bituminous, aqueous emulsion containing an emulsifying agent as well as colloidal clay and asphalt. This bonding agent is preferably painted on or otherwise applied to the walls of the depressions or indentations 36 prior to filling them with the moldable material itself. The latter may comprise a graded light-weight cellular burned argillaceous, chemically inert aggregate, such as silioxide rock or a volcanic ash. The asphaltic base may be a product similar to the bonding agent; that is, a bituminous, aqueous emulsion containing a colloidal clay but, unlike the bonding agent, also containing a non-mineral fibre. The setting powder may be air entrained cement blended with other cement powders, such for example as a Portland puzzolan-type cement.

The ingredients mentioned may be mixed with water to form a mortar-like product which can be treated with a trowel or otherwise easily molded or worked to fill each depression or indentation 36. A commercial product which is a composition of matter of the foregoing general type has been employed successfully as the filling material for the depressions or indentations 36. The mastic products mentioned above provide

at smooth line of juncture with the surface of the panel 29 so that the composite load-bearing surface of the member 27 is smooth and planar. Also, this surface possesses a comparatively high coefficient of friction so that articles supported by it have a relatively large angle of repose. For instance, the particular mastic material mentioned has a coefficient of friction of .47 when dry and .57 when wet as compared with a coefficient of friction of approximately .15 for a steel surface. Not only does the filler for the depressions 36 provide a smooth non-skid surface but it prevents foreign substances, such as soil, water, dirt, etc., from collecting in the depressions from which it would be difficult to remove them.

While the structural members 27 may be formed from any suitable metal, it is my opinion that it is practical to fabricate them from steel only, since this material is inexpensive, strong, and forms a satisfactory bond with the mastic filling material. It is preferable to use sheet steel which may be either hot or cold formed. However, it is preferable to form the depressions or indentations 36 by a hot-forming operation in most cases. For the lighter gauges, it would appear feasible to form the depressions or indentations by suitable metal working operations such as drawing, and to bend sheet stock to provide the webs 30 and 31 as well as the flanges 32 and 33.

It will be appreciated that the floor structural members of the present invention are stronger than comparable members produced heretofore and in addition provide a non-skid load-bearing surface. Furthermore, because of their increased strength, the present floor members not only provide a more satisfactory and durable floor, but permit a freight car frame structure to be simplified, especially through the elimination of at least two of the longitudinal floor supporting members now customarily utilized. However, the present floor members are readily adapted for use with conventional freight car frames, such as the one illustrated in the drawings or other standard types. These members are easily replaceable since each one is fixed in place independently of its neighbors, and is spaced from adjacent members at each side. While I have illustrated and described my invention chiefly in connection with the particular type of box-car mentioned, it will be understood that the invention is applicable to other structures, such as the simplified box car discussed immediately above, gondolas, trucks, ships, warehouses or the like.

I claim:

1. In a freight conveyance of the type in which freight in transit is subject to forces tending to move the freight relative to the conveyance, the combination comprising, a conveying supporting structure mounted for movement which sets up the forces and a metallic floor structure carried thereby, to which blocking can be nailed for preventing shifting of freight in transit, the metallic floor construction including a plurality of long, narrow metallic structural members arranged side by side, each structural member including a panel having a freight engaging face directed away from the conveying supporting structure, the freight engaging faces of the plurality of structural members having a relatively low coefficient of friction and being arranged at a uniform level to form the surface of the floor, a pair of side reinforcing webs joined to each

panel along the side edges thereof and extending laterally from the panel in a direction toward the conveying supporting structure, a flange joined to at least one web on each structural member and extending laterally from said web along the edge removed from the panel, said flange being in engagement with the conveying supporting structure, means including a rigid connection between flanges of the structural members and the conveying supporting structure integrating the metallic floor construction and conveying supporting structure and holding the structural members in side by side relation in the conveyance with the opposed webs of adjacent structural members contiguous to form a slot therebetween, the opposed webs being shaped and spaced to receive snugly therebetween a nail driven into the slot, means acting between the opposed webs for deforming and retaining a nail driven into the nail slot, a plurality of closely spaced depressed reinforcing ribs formed in the freight engaging face of each panel, the ribs extending transversely of the length of the panel and substantially from web-to-web, a settable initially moldable material filling the depressions in the freight's engaging faces presented by the reinforcing ribs to form a substantially plane surface on the panels of the structural members, the moldable material having a rock-like quality when set with the exposed surface thereof having a relatively high coefficient of friction, the faces of the panels and the entrances to the nailing slots being exposed for engaging freight and receiving nails for blocking the freight, respectively, and a closure means of mastic material closing the entrance to each nailing slot along the length of the nailing slot at substantially the level of the surface of the floor.

2. In a freight conveyance of the type in which a freight in transit is subject to forces tending to move the freight relative to the conveyance, the combination comprising, a conveying supporting structure mounted for movement which sets up the forces and a metallic floor construction carried thereby to which blocking can be nailed for preventing shifting of freight in transit, the metallic floor construction including a plurality of long, narrow metallic structural members arranged side by side, each structural member including a panel having a freight engaging face directed away from the conveying supporting structure, the freight engaging face of the plurality of structural members having a relatively low coefficient of friction and being arranged at a uniform level to form the surface of the floor, a pair of side reinforcing webs joined to each panel along the side edges thereof and extending laterally from the panel in a direction towards the conveying supporting structure, a flange joined to at least one web on each structural member and extending laterally from said web along the edge removed from the panel, said flange being in engagement with the conveying supporting structure, means including a rigid connection between flanges of the structural members and the conveying supporting structure integrating the metallic floor construction and conveying supporting structure and holding the structural members in side by side relation in the conveyance with the opposed webs of adjacent structural members contiguous to form a slot therebetween, the opposed webs being shaped and spaced to receive snugly therebetween a nail driven into the slot, complementary corrugations in the opposed webs extending in the direction of

the length of the webs for deforming and retaining nails driven into the nailing slots, a plurality of closely spaced depressed reinforcing ribs formed in the freight engaging face of each panel, the ribs extending transversely of the length of the panel and substantially from web to web, a settable initially moldable material filling the depressions in the freight engaging faces presented by the reinforcing ribs to form a substantially plane surface on the panels of the structural members, the moldable material having a rock-like quality when set with the exposed surface thereof having a relatively high coefficient of friction, the faces of the panels and the entrances to the nailing slots being exposed for engaging freight and for receiving nails for blocking the freight, respectively, and a closure means of mastic material closing the entrance to each nailing slot along the length of the nailing slot at substantially the level of the surface of the floor.
